UNITED STATES PATENT OFFICE.

CHARLES C. SMITH, OF EXETER, NEBRASKA.

GUIDE FOR INDEX-CARDS.

1,258,263.

Specification of Letters Patent.

Patented Mar. 5, 1918.

Application filed April 7, 1915. Serial No. 19,712.

To all whom it may concern:

Be it known that I, CHARLES C. SMITH, a citizen of the United States, and a resident of Exeter, in the county of Fillmore and 5 State of Nebraska, have invented a new and Improved Guide for Index-Cards.

My invention relates to metallic guides to be clipped to index cards. Guides of the indicated character include clamp jaws to 10 attach the guide to the card, and jaws at the opposite edge to hold a label.

A prime object of my invention is to provide an improved guide having jaws for receiving a label, the jaws being so formed 15 as to present an interior space to accommodate a label, and front longitudinal edges in close relation retaining the label at the front thereof, the jaws furthermore presenting end edges in close relation to prevent displacement 20 of the label at the ends of the guide.

A further object of my invention is to make provision for the entrance of the label with facility, the arrangement being such that the label may be readily entered and 25 will be effectively prevented from accidental displacement.

A further object of the invention is to provide a guide having provision for facilitating the removal of the label when desired.

30 The arrangement also has for its object to provide a guide of the indicated character, composed of resilient side plates so formed and united as to facilitate the manufacture, and provide efficient clamp jaws to engage 35 the ticket and receive the label.

The invention will be particularly explained in the specific description following.

Reference is had to the accompanying drawings forming part of this specification, 40 in which similar characters of reference indicate corresponding parts in all the views, and in which:

Figure 1 is a front view of my improved guide showing the same applied to an index card, illustrated in part, and carrying a 45 label;

Fig. 2 is a vertical transverse section on an enlarged scale on the line 2—2, Fig. 1;

Fig. 3 is a front view of the guide on an 50 enlarged scale;

Fig. 4 is a front edge view;

Fig. 5 is an end view;

Fig. 6 is an end view of the two plates from which the guide is formed, the view

showing the plates before compressing and 55 uniting the same;

Fig. 7 is a front view similar to Fig. 1, but indicating the manner of inserting the label;

Fig. 8 is a view similar to Fig. 7 showing 60 the manner of removing the label; and

Fig. 9 is a front view showing a slight modification.

In carrying out my invention in practice, in accordance with the illustrated example, 65 two similar resilient plates 10 are provided which are initially of general dished form vertically, the plates each presenting a depression between the opposite longitudinal edges, as shown in Fig. 6. The plates near 70 one edge comprise longitudinal members to constitute clamp jaws 11 for clamping the guide on a card A, the jaws meeting along the longitudinal edges 12. At the opposite edges the plates 10 are formed to constitute 75 jaws 13 for detachably holding a label B, bearing any suitable name or indicia, such as "Washington, D. C." the said jaws 13 meeting at the longitudinal edges 14.

The plates 10, in forming the guide, are 80 placed back to back as in Fig. 6, with the longitudinal edges 12 and 14 in contact; the plates are then placed under pressure to compress them laterally against their resiliency, so that they will contact along an intermediate longitudinal zone 15. The plates are then permanently united along said zone by electric welding, riveting, or other approved means, as indicated at 16. Thus the 85 jaws 11 and 13 will have effective resiliency, 90 and the zone 15 will limit the entrance of a card A and the label B. The label will be displayed through oblong openings 13^a formed in the jaws 13.

Various means have been proposed, and 95 different ways have been employed in practice to retain the label and to permit its removal. In my improved guide the jaws 13 at the end edges are swaged toward each other as at 17 from points adjacent to the 100 compressed and united zone 15 outwardly, the swaged edges 17 terminating, however, short of the front edges 14. There will thus be presented at the outer terminals of the swaged members 17, openings 18 at the ends 105 of the front edges 14, said openings communicating with the interior space provided between the jaws to accommodate the label.

B. The label may include a celluloid or equivalent U-shaped covering B¹ as illustrated in Fig. 2. With the described construction, a card B may be first entered 5 edgewise in either opening 18 and moved between the front edges 14, thus separating the jaws to permit the label B to enter and be accommodated between the jaws. The front edges 14, when the jaws close, will 10 prevent escape of the label at the front, while the swaged edges 17 will prevent displacement at the ends.

In order to provide for readily removing a label B or changing the same if desired, I 15 provide notches 19 in the jaws 13, one notch being sufficient in each jaw; these notches are located at the inner sides of the openings 13^a and permit the entrance of a pin or pencil, as conventionally indicated at C in Fig. 20 6 beneath the inner edge of the label, whereby to force said label outwardly through the front edges 14.

In the form shown in Fig. 9, the guide is 25 formed from plates 10^a essentially the same as described, having jaws 11^a with meeting edges 12^a and jaws 13^b with meeting edges 14^a, together with openings 13^c to display the label and notches 19^a corresponding with the notches 19. In the modified form a similar effect is produced by swaging the end 30 edges 17^a nearer to the front edges, but in this form also the swaged edges 17^a terminate short of the front edges 14^a, so that end openings will be presented at the ends of 35 the front edges as at 18^a to serve the described purpose of the openings 18.

By thus forming the sides from two separate resilient plates, shaped as described, and compressed and united along the intermediate 40 zone, a very efficient guide is cheaply and quickly produced, having great strength and durability, and affording facility for the entrance and removal of the label as well as insuring that the label will 45 be unfailingly retained against accidental displacement.

Having thus described my invention, what I claim as new and desire to secure by Letters Patent, is:

1. A label holder, comprising a pair of 50 dished jaws adapted to receive a card so as to lie wholly between the jaws, said jaws having oblong openings in their sides and having their end edges in contact for the greater portion of their length, the remaining outer portions of said edges being spaced apart forming openings, whereby provision is made for facilitating the insertion of a card between the jaws and for preventing an inserted card from displacement at the 55 ends of the jaws when the said jaws are closed.

2. A guide for index cards, formed of resilient side plates having clamp jaws at one edge to receive a card and clamp jaws at the opposite edge to receive a label, said latter jaws yieldingly meeting along the front and swaged along the side edges from points short of the front edges, the label holding jaws furthermore presenting an interior 70 space to accommodate a label within said front and side edges and presenting end openings communicating with the said interior space adjacent to the front edges for entering a label between the jaws. 75

3. A label holder comprising two pairs of oppositely projecting jaws, one pair serving to secure the holder to a card and the other pair to hold a label wholly within the jaws, the last named jaws having oblong 80 openings in their sides and notches in the bottom walls of said openings, the said jaws having the outer portions of their end edges spaced apart and the inner portions in contact. 85

In testimony whereof I have signed my name to this specification in the presence of two subscribing witnesses.

CHARLES C. SMITH.
